DISPENSING DEVICE FOR COLLAPSIBLE TUBES

Horace H. Miles, San Francisco, Calif.

Application April 13, 1932. Serial No. 604,974

5 Claims. (Cl. 221—60)

My invention relates to improvements in dispensing devices for collapsible tubes and the like wherein a pair of pinions mounted in engaging relation with a pair of depressed racks upon either side of a longitudinally disposed raised bed portion are connected rigidly by a roller of smaller diameter than the diameter of the pinions, said roller and pinions of different diameters thus operating in conjunction with said raised bed portion to completely extrude the contents of a collapsible tube on said bed portion by a rolling, and also a rubbing, movement toward the dispensing end of said tube when said rollers are rolled upon said racks and toward the said dispensing end, whereby the contents of said tube may be efficiently and completely extruded.

The primary object of the present invention is to provide a new and improved dispensing device for collapsible tubes and the like.

Another object of the present invention is to provide a new and improved device of the character set forth which is extremely simple and economical in construction and operation and which will provide an improved means for completely extruding the contents of a collapsible tube.

A further object is to provide an improved dispensing device for collapsible tubes and the like, which will impart a rolling, and also a rubbing, motion or movement toward the dispensing end of said tube while collapsing the tube whereby the same may be efficiently collapsed and the contents thereof completely removed.

A still further object of the present invention is to provide a new and improved device as described which may be easily constructed of sheet metal to provide a maximum economy of construction and the fewest possible number of parts.

The invention consists in the particular arrangement and construction of the parts disclosed in the drawing forming a part of the present application, wherein like characters of reference are used to designate similar parts throughout the said specification and drawing and in which—

Fig. 1 is a vertical, longitudinal, sectional view of my improved device, disclosing a collapsible tube partially extruded of its contents;

Fig. 2 is a broken plan view thereof with the cover removed;

Fig. 3 is a transverse sectional view taken on line 3—3 of Fig. 1 in the direction indicated; and

Fig. 4 is a similar transverse sectional view

disclosing a modified form of the improvement.

Referring to the drawing, the numeral 1 is used to designate in general a body formed preferably of sheet-metal, or the like, and having a centrally disposed longitudinal raised bed portion 2 with depressed portions 3 lying upon each side thereof and perforated to provide a pair of racks 4. Mounted in engaging relation with said racks, is a pair of pinions 6 rigidly connected by a roller 7 of smaller diameter than the pitch diameter of the pinions 6, the purpose of which will hereinafter be more fully set forth, said roller 7 lying in close proximity and extending transversely across said bed portion 2 of the body 1.

The pinions 6 are each provided with an extending trunnion 8 which are engaged by longitudinally disposed ribs 9 formed integral with the body 1 and extending longitudinally thereof and over the said trunnions 8 in order to retain the pinions 6 in engaging relation with their respective racks 4, as disclosed in Fig. 3 of the drawing.

One end of the body 1 is provided with an extended portion 11 apertured centrally as at 12 to receive and retain the neck or dispensing end 14 of a collapsible tube 16 upon the bed portion 2 of the device.

In Fig. 4 of the drawing I have disclosed a modification wherein the trunnions 8' are extended exteriorly of the body 1, thru longitudinally disposed slots 9', which take the place of the ribs 9, to retain said pinions 6 in engaging relation with their respective racks 4. The trunnions 8' are provided with suitably knurled knobs 17 whereby the device may be operated from the outside of the device.

A suitable cover 18 may be provided.

In operation, the collapsible tube 16, or the like, is placed upon the bed portion 2 and the dispensing end 14 of said tube 16 inserted thru the aperture 12 of the extension 11 and the roller 7 is then rolled upon the opposite flattened end of said tube 16.

When it is desired to extrude a portion of the contents of the tube 16, the pinions 6 are rolled upon their respective racks 4 and, by reason of the smaller diameter of the roller 7, the tube 16 will be collapsed upon the bed portion 2 by the roller 7 lying in close proximity thereto with a rolling, and also a rubbing, motion toward the dispensing end of said tube 16 whereby the contents of said tube may be completely extruded as the roller 7 passes over it.

I am aware that the present state of the art 110

discloses dispensing devices for collapsible tubes, and the like. I therefore, do not wish to include such a device broadly, but—

Having thus described my invention, what I claim and desire to secure by Letters Patent is—

1. A dispensing device for collapsible tubes comprising a body provided with a centrally disposed longitudinal bed portion and a depressed

10 rack on each side of said bed portion; a pair of pinions mounted in engaging relation with

said racks; and a roller of a lesser diameter than the pitch diameter of the pinions rigidly connected to said pinions and lying in close

15 proximity to said bed portion whereby the con-

tents of a collapsible tube upon said bed portion may be extruded from said tube by a rolling, and also a rubbing, movement towards the

dispensing end of said tube by said roller when

20 said pinions are moved along their racks toward said dispensing end whereby said contents may be substantially entirely removed from said

tube.

2. A dispensing device for collapsible tubes comprising a body provided with a centrally dis-

25 posed longitudinal bed portion and a depressed rack on each side of said bed portion; a pair of

pinions mounted in engaging relation with said

racks; a roller of a lesser diameter than the

30 pitch diameter of the pinions rigidly connected

to said pinions and lying in close proximity to

said bed portion whereby the contents of a col-

35 lapsible tube upon said bed portion may be ex-

truded from said tube by a rolling, and also a

rubbing, movement towards the dispensing end

35 of said tube by said roller when said pinions

are moved along their racks toward said dis-

40 pensing end whereby said contents may be sub-

stantially entirely removed from said tube; and

45 longitudinally disposed ribs formed integral

50 with said body for retaining said pinions in en-

gaging relation with said racks.

3. A dispensing device for collapsible tubes comprising a body having a centrally disposed

55 longitudinal body portion and a depressed por-

60 tion on each side thereof perforated to form

65 racks; a pair of pinions mounted in engaging

70 relation with said racks and each having a

75 trunnion projecting therefrom; and a roller of

80 smaller diameter than the pitch diameter of

85 said pinions rigidly connecting said pinions and

90 lying in close proximity to said bed portion,

whereby the contents of a collapsible tube upon said bed portion may be extruded therefrom by a rolling and also a rubbing movement toward the dispensing end of said tube by said roller when said pinions are moved along their racks toward said dispensing end, whereby said contents may be substantially entirely extruded from said tube.

4. A dispensing device for collapsible tubes comprising a body having a centrally disposed

25 longitudinal body portion and a depressed por-

95 tion on each side thereof perforated to form

racks; a pair of pinions mounted in engaging

30 relation with said racks and each having a trun-

nion projecting therefrom; a roller of smaller di-

ameter than the diameter of said pinions rigidly

40 connecting said pinions and lying in close

proximity to said bed portion, whereby the con-

45 tents of a collapsible tube upon said bed portion

50 may be extruded therefrom by a rolling and also a

55 rubbing movement toward the dispensing end of

60 said tube by said roller when said pinions are

65 moved along their racks toward said dispensing

70 end, whereby said contents may be substan-

75 tially entirely extruded from said tube; and

80 longitudinally disposed ribs formed integral with

85 said body and engaging the trunnions upon said

90 pinions for retaining said pinions in engaging

95 relation with said racks.
